TIRE RACK

Emanuel J. Zinna, 28 Holly Drive,
Sayville, N.Y. 11782

Filed May 22, 1974, Ser. No. 472,123

Term of patent 14 years

Int. Cl. D6—04

U.S. Cl. D6—85

FIG. 1

FIG. 2

FIG. 3

FIG. 4

FIG. 5

FIG. 1 is a perspective view of a tire rack showing my new design;

FIG. 2 is a top plan view thereof;

FIG. 3 is a front elevational view thereof;

FIG. 4 is a right side elevational view thereof, the left side being a mirror image thereof; and

FIG. 5 is a bottom plan view thereof.

I claim:

The ornamental design for a tire rack, substantially as shown.

No references cited.
